United States Patent Office

Des. 197,661
Patented Mar. 10, 1964

197,661

CLOCK

Donald E. Leman, Chicago, Ill., assignor to Sunbeam
Corporation, Chicago, Ill., a corporation of Illinois

Filed June 8, 1962, Ser. No. 70,487

Term of patent 14 years

(Cl. D42—7)

Fig. 1.

Fig. 2.

Fig. 3.

Fig. 5.

Fig. 4.

Fig. 6.

FIG. 1 is a front perspective view of a clock showing my new design;

FIG. 2 is a rear perspective view thereof;

FIG. 3 is a side elevational view thereof;

FIG. 4 is a bottom plan view thereof;

FIG. 5 is a cross-sectional view thereof taken on line 5-5 of FIG. 4; and

FIG. 6 is a top plan view.

I claim:

The ornamental design for a clock, as shown.
